UNITED STATES PATENT OFFICE.

MAGNUS MÅNSSON, OF HELSINGBORG, SWEDEN.

SAIL-HANK.

No. 842,215.

Specification of Letters Patent.

Patented Jan. 29, 1907.

Application filed September 20, 1904. Serial No. 225,275.

To all whom it may concern:

Be it known that I, MAGNUS MÅNSSON, a subject of the King of Sweden and Norway, and a resident of Hittarp, Helsingborg, in the Kingdom of Sweden, have invented certain new and useful Improvements in Sail-Hanks, of which the following is a specification, reference being had therein to the accompanying drawings.

10 This invention relates to a sail-hank consisting of two parts hinged together, this sail-hank being arranged in such a manner that the parts form two closed loops when the sail-hank is closed, the joint not being in the path 15 of any of the ropes running in the hank, whereby the parts of one of the loops form a sister hook locking automatically in order to produce an easy opening and closing of the sail-hank, as more fully hereinafter described.

20 In order to enable this invention to be readily understood, reference is made to the accompanying drawings, in which—

Figure 1 shows hanks arranged in accordance with this invention and employed for 25 fixing a staysail to the stay. Fig. 2 is a plan view of one of the hanks in its closed position. Fig. 3 shows the hank in the opened position. Fig. 4 is an edge view of the hank in the closed position. Fig. 5 is an edge view 30 of the same at the first stage of the opening operation.

As seen from Figs. 2 and 3, the hank consists of a part formed into two open loops *a* and *b*, forming together a figure substantially resembling the numeral **3**. With the free end of the greater loop *a* a hook *c* is connected by a hinge-joint *k*, said hook having such a shape that when closed onto the loop *b* the loops *a*, *b*, and *c* form two closed circular or substantially circular rings, of which the greater one is adapted to inclose the stay *d* and the smaller one is adapted to be hooked in the loops or the bolt-rope *e* of the sail *f*, Fig. 1. As seen from Figs. 2 and 4, the hook *c*, when the hank is closed, is situated at the 45 side of the loop *b* and close to the same. The sides of the loop *b* and the hook *c* facing one another are plane and cut obliquely in such a manner that when put together they form a

ring, being circular or elliptic in cross-section. 50 When the sail is strained, the hank is subjected to a tension along or substantially along the center line *g g*, Fig. 2, and the bolt-rope *e* in the sail bears against the loop *b*, as well as the hook *c*. In this manner accidental opening of the hank—as for instance, by violent gusts of wind—is entirely obviated. 55

In order that the loop *b* and the hook *c* may be positively locked to each other when overlapping one another, the loop *b* is provided with a pin *h* perpendicular to its oblique face, the pin entering a corresponding recess *i*, provided in the oblique face of the hook *c*. The parts *b* and *c* are flexible to some degree in order to enable them to bend 65 from each other, as shown in Fig. 5, when the hank is to be opened. The point of the pin *h* slides along the plane side of the hook *c* when the hank is being opened or closed, and the pin snaps into the said recess *i* when the hank 70 is closed, thus locking the hook in a reliable manner. The part or ring *a* of the hank inclosing the stay *d* is, as seen from Fig. 2, quite circular and has no recesses into which the stay can enter and be caught. 75

Having now described my invention, what I claim as new, and desire to secure by Letters Patent, is—

A sail-hank consisting of a part having the form of the numeral **3**, the upper or smaller section of which comprising an arc of about two hundred and seventy degrees, and the lower or larger section comprising an arc of about two hundred and eighty degrees and a second part hinged to the extremity of the lower section of said first part, said second part comprising an arm completing the circle of said lower section and a portion forming a sister hook with said upper section of the said first part. 80 85 90 95

In witness whereof I have hereunto signed my name, this 3d day of September, 1904, in the presence of two subscribing witnesses.

MAGNUS MÅNSSON.
